LASTING MACHINE

Josef Zaoral, Zlin-Dily, and Vilém Ostrčil, Horní Mostenice, Czechoslovakia, assignors to Bata, národní podnik, Zlin, Czechoslovakia

Application March 25, 1947, Serial No. 737,075
In Germany April 5, 1945

Section 1, Public Law 690, August 8, 1946
Patent expires April 5, 1965

5 Claims. (Cl. 12—12.4)

1

This invention relates to an improvement in or a modification of the driving means for the shaping and smoothing device in shoe-end tacking machines, more particularly toe tacking machines.

The main function of the shaping and smoothing device of such machines is to pull over the upper part of the shoe, which is firmly held and tensioned by tensioning nippers, in the direction towards the last edge, to embrace the part of the shoe in question along the last edge and thereby to secure the tensioned and pulled over upper part after the release of the tensioning nippers. The smoothing device wipes and then lays the projecting marginal portions of the upper part over the last edge and the inner sole, in which position the said marginal portions are tacked to the inner sole by fixing means, by the use of an adhesive or the like means. With this object in view the shaping device consists usually of a flexible band which is pressed by a system of levers or by springs against the periphery of the shoe, whilst the wipers are formed by two flat pieces of iron, the shape of which corresponds to that of the shoe toe or of the heel part and which are moved forwards and backwards with respect to the shoe last and at the same time perform a swinging closing motion. The shaping device and the wiping device are arranged in the usual manner in a common arm, to which is imparted a swinging motion in the direction towards the shoe to be operated on, in order to bring about the pulling over action of the former on the upper part in the direction towards the last edge.

This swinging motion of the arm supporting the shaping and smoothing device, the closing of the former, the pushing forward and the closing of the wipers has hitherto been effected independently in each case by a complicated system of levers, pull rods and gear wheels from cams, a separate cam being provided for each of these motions. In view of various inaccuracies in the material forming the upper parts, the lasts and the like, it is necessary to make the positive motion of the said parts, that is, the arm, the former and the wipers, yielding within a certain range, in order that the material of the upper part shall not be damaged by the action of the devices. With this object in view yielding members are interposed in the system of driving levers. The give in the positive drives of the devices is, however, not sufficiently great to render unnecessary and adjustment of the drives or the former and the wipers, when changing from one kind

5 or size of shoe being operated on to another. For these reasons the whole construction of the devices becomes very complicated and, consequently, also uneconomical. Furthermore, the employment of the positive drive of the former, the wipers and the common arm, which is yielding only to a limited extent, necessitates the shoe being fixed in the machine very accurately. For this purpose it is the usual practice to provide the last and also the inner sole with bores, by means of which the exact position in the shoe holder is ensured by pins.

10 According to the present invention a considerable simplification of the driving means of the former, the wipers and the arm itself together with a substantial reduction of the danger of injury to the upper part, a simpler manipulation both of the work and of the machine is effected.

15 The essential feature of the present invention is, that the drive of the former, the wipers and the common arm itself supporting the operating device is effected hydraulically in such a manner that parts of the operating devices are in direct connection with the piston rods of pressure cylinders intended for the control of these devices, the operative strokes of individual parts not being determined from the outset, but proceeding up to impact against the work and thus adapting themselves automatically to the shape and size of the latter. The consequence of this is, that, on the one hand, the usual adjustment of the devices for different shapes and sizes of shoe becomes superfluous and, on the other hand, the shoe can be placed in the machine in the usual, simple manner, merely so that it bears 20 against a toe stop on the shoe holder and with the marginal portions of the upper part inserted between the nippers, as is done, for instance, in the known pulling over machines. The pressure cylinders for the control of the wipers are mounted directly in the swingable arm, so that any necessary dismantling is very simple. For a toe tacking machine the former is preferably made such that it embraces the forward part of the shoe from the toe to the waist part.

25 Further advantages and features of the present invention will be gathered from the description of a constructional example according to the invention with reference to the accompanying drawings, in which:

30 Figure 1 is a partial longitudinal section through the shaping and smoothing device of a toe tacking machine;

35 Figure 2 a plan view of Figure 1 seen from above and which shows in its upper part a toe former

and wiper extended and in its lower part the toe former and wiper retracted, and

Figure 3 a cross-section of Figure 1.

The shaping and the smoothing device is mounted on the common swingable arm 1 which itself is adapted to turn about the pin 2 fixed in the machine frame. The longer arm of this two-armed lever is forked and has at its end a head 3 with the actual operative devices, whilst to the shorter end is fixed a block 4 with pressure cylinders.

In the head 3 which, viewed from above (Figure 2), has the form of a Y there are provided in the two side parts keyways 5, each of which acts as a guide for a cranked bar 6. These bars are connected by means of grooved seating faces 7 and screws 8 each with a pull bar 9. By adjusting the grooved seating faces the length of the connection between the pull bars 9 and the cranked bars 6 can be easily altered. The pull bars 9 are connected by couplings 81 with the piston rods 10 of the pistons 11 which work in pressure cylinders 12, 12' mounted in the block 4. Each of these cylinders has an inflow opening 13 and an outflow opening 14. The openings are in communication through forked pipe connections 15, 16 each with a common supply and outlet for the pressure fluid. On the bars 6 are pivoted on pins 17 link members 18 which by means of pins 19 are connected each with one end of the flexible toe former 20 which is in the shape of a U and consists of a resistant, but yielding material. By a pin 21 the former 20 is rigidly connected with the head piece 3 of the swing ing arm 1 in the toe part.

In the middle part of the head piece 3 there is provided a guide 22, in which a slide 23 is slideable (Figure 3), to the pin 24 of which (Figure 1) a pull bar 25 is attached, which is connected by means of a pin 26 with the piston rod 27 of the piston 28 which operates in the pressure cylinder 29 mounted in the block 4. In the slide 23 is a dove-tail groove 30 (Figure 3), in which a further slide 31 slides, which is connected by means of the pin 32 (Figure 1), the pull bar 33 and the pin 34 with the piston rod 35 of the piston 36, the latter operating in the pressure cylinder 37, also mounted in the block 4. In the slide 31 are inserted two vertical pins 38 (Figure 3), on which are pivoted from below two link members 39 which are connected by means of pins 40 each with a circular projection 41 (Figure 1) forming parts of the actual wipers 42. When the tacking is to be carried out by nailing, these wipers 42 are provided with a row of holes 43 (Figure 2), through which the nails pass, when being driven in. The circular projections 41 (Figure 1) of the wipers 42 are guided in a circular groove 44 of the slide 23 and are secured from below by a supporting plate 45. The to and fro motion of the slide 31 in the guiding groove 30 of the slide 23 therefore also produces a circular motion of the wipers 42 in the slide 23. The cylinder spaces 29 and 37 in front of the pistons 28 and 36 are in communication with one another through a duct 46, whilst the spaces behind these pistons are interconnected by a duct 47. These two working cylinders have a common inlet 48 and a common outlet 49.

The swinging motion of the arm 1 about the pin 2 is imparted to it by means of forked bars 50, the forked ends of which are suspended from gudgeons 51 (Figure 3) of the arm 1, whilst the lower ends are connected by pins 52 (Figure 1) with levers 53, the other ends of which are con-

nected by pins 54 with the piston rod 55 of the piston 56 working in the cylinder 57. The pressure cylinder 57 is mounted so as to be capable of rocking about a pin 58 fixed in the machine frame. The pin 54 is also pivoted in a bar 59 which is adapted to swing about a pin 60 fixed in the machine frame. The bars 50, 53, 55 and 59 thus form a toggle lever system which together with the working cylinder is rotatable about the pins 58 and 60. As will be seen from Figure 1, in the working position the bars 50 viewed from the side come into alignment with bars 53 and 59. Connections 83 and 84 lead to the pressure cylinder 57.

In order to make a swinging motion of the arm 1 impossible, when no work is clamped in the machine, the arm is in such a case secured directly by the support 61 (Figure 1) which is guided in a cylindrical guide 62 in the standard 63 and is acted on by a spring 64 which seeks to keep it forced upwards. The spring 64 at the same time takes a pin 65 along with it, which at its lower end supports a small block 66 which is guided in a fork 67 of the two-armed lever 68. The two-armed lever is pivoted about the pin 69 and with its second arm engages in a slot 70 of the horizontally slideable plate 71, the right-hand end of which comes into engagement with the teeth 72 of the bars 50, on being displaced to the right, and thus prevents a downward movement of these bars 50. Only after the support 61 has been forced down, through the shoe being placed on and pressed against the support 61, will the lever 68 be swung by means of the pin 65 in the clockwise direction with a consequent displacement of the plate 71 to the left, so that the bars 50 are released. The support 61 is secured against turning by a screw 85 engaging in a groove 86 of the cylindrical guide 62.

The pressure-applying movement of the pressure-applying pad 73 against the shoe placed on the support 61 is also derived from the downward movement of the arm 1. The pressure-applying pad 73 is supported in a known manner so as to be vertically adjustable in a two-armed lever 74 which rocks about the pin 75 in the head piece 3. Mounted so as to rock on the same pin 75 is also a hollow arm 76, the cross-sectional form of which is seen in Figure 3 and which covers the right-hand arm of the lever 74. The lever arm 76 carries at its right-hand end a roller 77 which is in engagement with a cam surface 78. The arm 76 and the right-hand end of the lever 74 are connected with one another by means of a pin 79 and a spring 80 yieldingly in such a manner that, on the arm 76 swinging in the counter-clockwise direction, the spring 80 is compressed, on the pressure applying pad 73 bearing against the shoe, and so protects the upper part of the shoe from being overloaded.

The described arrangement operates in the following manner:

Before the shoe is placed in the machine and during the time in which the tensioning nippers 65 are acting on the upper part the arm 1 together with all its associated devices stands in the upwardly rocked position which is shown in dotted lines in Figure 1. All the pistons of the working cylinders 12, 12' (Figure 2), 29, 37 and 57 (Figure 1) are in their right hand extreme positions, the shoe former 20 and the wiper 42 are open, as shown in the lower half of Figure 2.

Through admitting pressure fluid into the cylinder 57 through the supply pipe 83 and connecting the pipe 84 to the outlet, the piston 56,

commences to move to the left, the angle which the link members 59 and 53 enclose commences to become greater, while at the same time the pins 52 move downwards with respect to the pin 60 and the bars 50 along with the arm 1 consequently move downwards in the lowest position, as shown in Figure 1. The bars 50 had previously been released from engagement with the plate 71 through the depression of the support 61, on the work being placed in position and the plate 71 displaced, as already described above.

During the downward movement of the arm 1 the roller 71 of the lever 76 rolls on the cam surface 78 and rocks the lever 76 about the pin 75 in the counter-clockwise direction. At the same time the arm 76 by means of the pin 79 and the spring 80 carries the two-armed lever 74 along with it and rocks the latter in the same direction about the pin 75. Through this movement the pressure-applying pad 73 is pressed against the shoe toe which is thus firmly clamped between the pressure-applying pad 73 and the support 61. The application pressure of the pad 73, corresponds to the force of the spring 80, since the pressure-applying pad 73 adjusts itself vertically in such a manner that the swing of the lever 76 is greater than the swing of the two-armed lever 74, the movement of which is ended by the pad 73 coming to bear on the shoe, whereas the movement of the lever 76 continues, at the same time compressing the spring 80.

While the lever arm 1 is still descending and as soon as the point of the former reaches the toe of the shoe, the closing movement of the former 20 commences, which is brought about through the admission of pressure fluid into the cylinders 12, 12' through the pipe 15. The pistons 11 of the pressure cylinders 12, 12' commence to move to the left and by means of the piston rods 10, the push bars 9, the cranked bars 6 and the link members 18 initiate the closing motion of the former 20. The working strokes of the pistons 11 of each cylinder only come to an end, when the associated side of the form 20 bears fully against the shoe. Since the former 20 preferably extends to the waist of the shoe, that is to say as far as places, where the shoe is no longer symmetrical, the movement of the two pistons 11 will not end simultaneously, as that part of the former 20 which comes into action on the shoe at the place of the arch of the foot, has to travel a longer distance, as this part lies nearer to the middle of the shoe. Irrespective of which part of the former travels further, or which piston 11 performs a longer stroke, the pressing pressure of the former will be equally great on both sides, as the working cylinders 12, 12', owing to the common inlets 15 and 16, actually represent communicating vessels. Through the co-action of the closing movement of the former 20 with the continuing rocking motion of the arm 1 downwards, on the one hand the known and requisite pulling over of the upper part on the last in the vertical direction is brought about and, on the other hand, a firm clamping of the upper part against the edge of the last is ensured, so that the stretched over upper part can finally be released from the known tensioning nippers which are not shown.

As soon as the arm 1 is in its lower position and the upper part is released by the nippers and is secured by the former 20 on the last in the tensioned position, the smoothing at the shoe toe by the wiper 42 can be initiated. For this purpose pressure fluid is admitted through the pipes

48, 46 into the pressure cylinders 37 and 29, whilst the pipes 47, 49 are connected to the outlet. The result of this is, that the wipers 42 which till then were open and together with the slide 23 were displaced to the right, as shown in the lower half of Figure 2, now commence under the action of the working strokes of the pistons 28 and 36 to move to the left, for the time being still in the open state, towards the shoe. Since the pressure cylinders 29 and 37 are in communication with one another through the duct 46 and form communicating vessels, the same pressure acts on both pistons 28 and 36, so that the latter commences to move simultaneously and at the same speed. Since the movement of the piston 28 to the left simultaneously causes a corresponding displacement of the slide 23 to the left in the guide 22 of the head 3, the simultaneous movement of the piston 36 will cause no relative displacement of the slide 31 in the dovetail groove 30 of the slide 23; no closing movement of the wipers 42 in the circular groove 44 will therefore yet take place. As soon, however, as the movement of the slide 23 is interrupted (in this case through the wiper 42 coming against the toe edge of the upper part of the shoe projecting downwards beyond the lower part of the last), the pressure in the pressure spaces of the working cylinders 29, 37 will immediately commence to rise. Since the slide 23 cannot for the time being move further, the pressure will commence to act on the piston 36 which, whilst the piston 28 has come to rest, moves further to the left and produces a relative movement of the slide 31 in the slide 23 to the left. In this relative movement the link members 39 force the wipers along the circular grooves 44 forwards, which results in a closing of the wipers. The closing movement of the pushing members 42 is obstructed by the marginal portions of the upper part, which projects downwards beyond the edge of the last, and the wipers bend these marginal portions of the upper part over the edge of the last and fold them over one another under the last. During the bending over and folding together the resistance offered to the wipers continuously increases, so that the pressure in the cylinders also rises and, under the reciprocal action between the pistons 28 or 36, according to the amount of the resistance, a constant equalisation between the displacement of the wipers to the left and their closing movement takes place. In order to be able to influence this reciprocal action between the pistons 28 and 36 according to requirement, it may be of advantage in some cases, to make the cross-sectional areas of flow of the connecting ducts 46 and 47 regulable. The displacement of the wipers to the left and the closing motion of the same is brought to an end through the projection 82 (Figure 1) coming against the outer periphery of the shoe form 20. As this form through pressing against the shoe adapts itself to the shape of the shoe, contact by the projection 82 ensures the correct position of the nail holes with respect to the edge of the shoe.

As soon as the movement of the wipers has come to an end, the tacking of the upper part of the shoe on to the inner sole can be started in the usual way, the fixing means being driven through the holes 43 in the wipers. The nailing device may be of any known construction. When fastening by means of an adhesive is to be employed, no holes 43 are required in the wipers 42 and the sticking process may be carried out with the pressure of the wipers which for this pur-

pose remain at rest for a certain time, according to the kind of adhesive employed.

After the completion of the fastening operation, whether this has been effected by nailing or with the aid of an adhesive, the arm 1 together with the shoe still clamped between the closed wipers, the former and the pressure applying pad 13 swings upwards. About half way through this swinging motion the pressure applying pad 13 is released through the co-action of the cam surface 78 with the roller 77 of the lever arm 76. The upward swinging motion of the arm 1 is brought about by the admission of pressure fluid into the pipe 84, whilst the pipe 83 is connected to the outlet. After the release of the pressure applying pad 13 the former 20 is opened, through the admission of pressure fluid into the pipe 16 (Figure 2) of the cylinders 12, 12', whilst the pipe 15 is connected to the outlet, and before the swinging movement of the arm 1 upwards is ended, the opening of the wipers 42 and their return into the initial position takes place through the admission of pressure fluid into the cylinders 29, 37 through the pipe 49, whilst the pipe 48 is connected to the outlet. After the opening of the wipers 42 the shoe will have become completely freed in the swinging arm 1 and lies free in the open hand of the worker. After the arm 1 has been returned into the position shown in Figure 1 in dotted lines, a complete operation of the described arrangement is ended.

The supply of the pressure fluid to the working cylinders takes place with advantage through flexible tubes and is regulated by slide valves of a known kind, which are automatically controlled by cams, for instance in the same way as the control of the pressure cylinders according to our concurrent patent application Serial Number 737,073.

We claim:

1. A shaping and smoothing device for shoe-end tacking machines, such as toe-tacking machines, comprising: a common swinging arm, a flexible toe former mounted on the common swinging arm, wipers on the flexible toe former, hydraulic pressure cylinders, and pistons working in the said cylinders for controlling the operative motions of the former and of the wipers, the flexible toe former and the wipers being directly connected with the said pistons, and the working strokes of the former and wipers proceeding up to impact against the work, so that they adapt themselves automatically to the shape and size of the work.

2. A shaping and smoothing device for shoe-end tacking machines, such as toe-tacking machines, comprising: a common swinging arm, a flexible toe former mounted on the common swinging arm, wipers on the flexible toe former, hydraulic pressure cylinders, and pistons working in the said cylinders for controlling the operative motions of the former and of the wipers, the pressure cylinders for the former and for the wipers being mounted in the swinging arm itself, and the working strokes of the former and wipers proceeding up to impact against the work, so that

they adapt themselves automatically to the shape and size of the work.

3. A shaping and smoothing device for shoe-end tacking machines, such as toe-tacking machines, comprising: a common swinging arm, a flexible toe former mounted on the common swinging arm, wipers on the flexible toe former, separate hydraulic pressure cylinders mounted in said arm for the two ends of the toe former, pistons working in the said cylinders for controlling the operative motions of the toe former, and common admission and exhaust pipes connecting the pressure spaces of these cylinders, so that the pressures at both ends of the toe former always remain equal, even when the ends of the toe former move by different amounts.

4. A shaping and smoothing device for shoe-end tacking machines, such as toe-tacking machines, comprising: a common swinging arm, a flexible toe former mounted on the common swinging arm, wipers on the flexible toe former, a separate hydraulic cylinder for the forward and backward sliding motions of the wipers, a separate hydraulic cylinder for the closing and opening motions of the wipers, pistons working in the said cylinders and connected to the wipers for controlling the operative motions of the wipers, ducts establishing communication between the cylinder spaces in both cylinders in front of and behind these pistons, so that pressure on both pistons can be applied simultaneously to advance the wipers into contact with the toe without closing movement and thereafter to impart closing movement and further advancing movement till the maximum pressure in both working cylinders is fully reached.

5. A shaping and smoothing device for shoe-end tacking machines, such as toe-tacking machines, comprising: a common swinging arm, a flexible toe former mounted on the common swinging arm, wipers on the flexible toe former, hydraulic means mounted in said arm for controlling the operative motions of the former and of the wipers, a pressure-applying pad for firmly holding the shoe toe, a two-armed lever pivoted on said arm and supporting the pressure-applying pad, a lever arm pivoted on said swinging arm and acting on the two-armed lever, a spring interposed between the lever arm and the two-armed lever, a roller on said lever arm and actuating the lever arm, and a cam fixed relative to said swinging arm and acting on the roller during the downward movement of the swinging arm to provide pressure-applying motion to the pad.
